COMBINED BOTTLE AND CLOSURE

Bishop McLeod, Wantagh, N.Y., assignor to Schenley
Industries, Incorporated, New York, N.Y., a corpora-
tion of Delaware

Filed Jan. 10, 1967, Ser. No. 5,375

Term of patent 14 years

(Cl. D9—83)

FIG. 5

FIGURE 1 is an exploded view of a combined bottle and closure embodying my new design;

FIGURE 2 is a side elevational view, the opposite side being a mirror image of the side shown;

FIGURE 3 is a top plan view thereof;

FIGURE 4 is a sectional view thereof taken on the line 4—4 of FIG. 3; and

FIGURE 5 is a fragmentary elevational view of the front of the closure and a portion of the bottle.

I claim:

The ornamental design for a combined bottle and closure, as shown and described.
